[57] ABSTRACT

A pair of transistors are connected to opposite ends of the magnet coil to be energized. A control pulse directly turns one transistor on and simultaneously fires a single shot multivibrator and its output turns on the other transistor. Current builds up in the coil during the single shot multivibrator time out period. The transistor controlled by the single shot multivibrator turns off when the single shot multivibrator times out. Coil current decreases but at slow rate as it circulates from one side of the power supply through a diode connected to one end of the coil and through the transistor connected to the other end of the coil back to the same side of the power supply. The dropping of the control pulse turns off the other transistor and the coil current rapidly decays to zero because the power supply is connected across the coil in a reverse direction via another diode connected to the other end of the coil and the other side of the power supply.

FIG. 2

MAGNETIC COIL DRIVER CIRCUIT

BACKGROUND OF THE INVENTION

1. Field of the Invention

This invention relates to magnet coil driver circuits and more particularly to an improved magnetic coil driver circuit having fast pick and drop out times and still more particularly to magnet coil driver circuits using the magnetic coil circulating current principle for energy transfer. The invention finds particular utility for energizing magnet coils of print hammers or punch actuators which operate at relatively high repetition rates.

2. Description of the Prior Art

In the past, most magnet coil driver circuits have used a combination of transistors with resistors and capacitors to achieve high speed operation. Although those circuits usually operate satisfactorily, they consume more power and use components of larger physical size than the present invention. Hence, the present invention results in improved cost performance because the power supply requirements are reduced and the magnet driver circuit can be packaged more efficiently. The efficiency of the magnet driver circuit of the present invention is improved because without a resistor in the circuit, the full power supply voltage is available for both energizing and de-energizing the magnet coil.

SUMMARY OF THE INVENTION

The principal objects of the invention are to provide an improved magnet coil driver circuit which: (a) operates with relatively little energy dissipation; (b) operates at relatively high repetition rates; (c) operates efficiently; (d) is made up of components adapted to be easily packaged; and (e) is relatively inexpensive.

The foregoing objects are achieved by selectively connecting the full power supply voltage across the magnet coil. This quickly energizes the coil and then after the coil is energized to a desired current value as determined by a time delay one side of the power supply is disconnected from the coil. The coil current slowly decays but continues to circulate to provide a magnetic field of sufficient strength over a period of time to the desired work to be performed. The coil current is then quickly removed from the coil by connecting the full power supply voltage across the coil in a reverse direction. The time delay can be introduced in many ways depending upon the machine or system incorporating the magnet coil. For example, in some instances, the delay can be developed by a time delay circuit and in other instances microprogramming can be used if available. Desired time delays can be generated based upon a microprogram routine having repetitive micro instruction cycle times where the number of repetitive micro instruction cycle times determines the amount of time delay.

BRIEF DESCRIPTION OF THE DRAWINGS

FIG. 1 is a schematic circuit diagram illustrating the invention; and,

FIG. 2 is a waveform diagram for the circuit of FIG. 1 where waveform A represents the input control signal, waveform B shows the output pulse from the single shot multivibrator, waveform C represents the voltage signal at the collector of one control transistor, wave-

form D represents the voltage signal at the emitter of the other control transistor and waveform E represents the current in the magnet coil.

DESCRIPTION

With reference to the drawings and particularly to FIG. 1, the invention is illustrated by way of example as magnet driver circuit for energizing magnet coil 10. Magnet coil 10 can be any magnet coil such as the type used for print and punch magnet actuators in I/O devices for a computer system. The magnet coils in such devices are operated in response to a command or control signal which in this instance is shown as waveform A in FIG. 2 and is applied to input terminal 15 in FIG.

15 1. The input terminal 15 is connected to both pre-driver 20 and single shot multivibrator 25. The output of single shot multivibrator 25 is connected to pre-driver 30 and the outputs of pre-drivers 20 and 30 are connected to the bases of transistors T1 and T2 respectively.

Transistors T1 and T2 are conventional NPN switching transistors with the collector and emitter of transistor T2 connected to the +Vs terminal of the power supply and to one end of coil 10 respectively. The collector and emitter of transistor T1 are connected to the other end of coil 10 and to the ground potential terminal of the power supply, respectively. The end of coil 10 connected to the emitter of transistor T2 is also connected to the cathode of diode D2. The anode of diode D2 is connected to the ground potential terminal of the power supply. The other end of the coil, i.e., the end connected to the collector of transistor T1 is also connected to the anode of diode D1. The cathode of diode D1 is connected to the +Vs terminal of the power supply. Transistors T1 and T2 are normally off and thus diodes D1 and D2 are reverse biased and no current normally flows in coil 10.

When a positive going signal is applied to input terminal 15, single shot multivibrator 25 fires and both pre-drivers 20 and 30 generate a positive going signal to turn transistors T1 and T2 on. Pre-drivers 20 and 30 are conventional pre-driver circuits and function to amplify the current of the signals for turning transistors 45 T1 and T2 on. With transistors T1 and T2 on a current path is established from the +Vs terminal of the power supply through transistor T2, through coil 10, and through transistor T1 to the ground potential terminal of the power supply.

50 Current rapidly builds up in coil 10, see waveform E, until single shot multivibrator 25 times out. The current peak value in coil 10 is proportional to the time period of single shot multivibrator 25, i.e., $i_L(t) = V_s(t)/L$ where t equals the time period of the single shot multivibrator 25, V_s is the power supply voltage and L is the inductance of coil 10. Transistor T1 turns off when single shot multivibrator 25 times out. The signal from single shot multivibrator 25 is represented by waveform B in FIG. 2. This causes the collector voltage of transistor T1 to go positive, as shown by waveform C, to forward bias diode D1 whereby current flowing in coil 10 continues to flow but decreases as represented in waveform E at a relatively slow rate for the time t_d . The current circulating in coil 10, under the conditions just mentioned, is from the +Vs terminal of the power supply, through transistor T2, through coil 10, and through diode D1 back to the +Vs terminal of the power supply.

55 60 65

Hence, the current in coil 10 at this time is approximately:

$$i(t)/t = (VT2 + VD1)/L$$

The current decay occurs slow enough that the electro- 5 magnet performs its intended function.

The coil 10 is de-energized rapidly by turning off transistor T2. This occurs when the input signal goes to a down level as represented by waveform A. With T2 off, its emitter voltage goes negative, as represented by waveform D, to forward bias diode D2. This places the power supply across coil 10 in a reverse direction and the current therein decays rapidly as it reverses direction as seen in waveform E.

Various other techniques may be used to control the turn off of transistor T1 without departing from the spirit of the invention. The time delay, of course, effects the amount of current conducted by transistors T1 and T2. Hence, if for some applications it is necessary to maintain current in the magnet coil for relatively long periods of time, intermittent time delays can be used, i.e., multiple single shots or multiple delay circuits. Thus the coil current would decay after the first time delay times out but would again increase when the next time delay is initiated. In this way the coil current could be maintained for a relatively long period of time without exceeding the current ratings of transistors T1 and T2. The same type of action can be achieved with microprogramming control. One microprogram control routine can develop one time delay period and a subsequent microprogram control routine or the same one can be called at a later time to initiate another time delay period. The magnet current, if desired, can be maintained over a longer period of time by adding inductance in series with the magnet coil to decrease the 35 amount of decay of the circulating current.

From the foregoing it is seen that the invention provides an improved magnet coil driver circuit which because of its fast response time can operate at relatively high repetition rates. Further, the invention keeps power dissipation to a minimum, because the power is primarily reactive power and the true power is limited to the power consumed by the transistors T1 and T2 and diodes D1 and D2 which is minimal.

What is claimed is:

1. A magnetic coil driver circuit comprising:
a source of power supply voltage,
circuit means including first and second current switches for connecting said magnet coil directly across said power supply voltage in one direction, and first and second unilateral current conducting devices responsive to being forward biased for connecting said magnet coil across said power supply voltage in a reverse direction, and
control means for selectively operating said circuit means to first simultaneously turn said first and second current switches on to connect said magnet coil directly across said power supply in one direction and thereby energize said coil whereby the coil current rises linearly and reaches a level determined by said power supply voltage, the length of time said coil is energized, and the inductance of said coil and after a predetermined time delay turn off said first current switch to allow current circu- 55

lating in said coil to decay whereby said circulating current maintains said coil energized with a holding current and then turn off said second current switch prior to said circulating current dropping below holding current level whereby said first and second unilateral current conducting devices connect said magnet coil across said power supply in said reverse direction to de-energize said magnet coil.

10. The magnet coil driver circuit of claim 1 where said first and second current switches are transistors.
3. The magnet coil driver circuit of claim 1 where said first and second unilateral current conducting devices are diodes.
15. The magnet coil driver circuit of claim 1 wherein said control means includes a single shot multivibrator for generating said predetermined time delay.
5. A magnetic coil driver circuit comprising:
a source of power supply voltage,
a first transistor connected to one side of said power supply voltage and to one end of said magnet coil, a second transistor connected to the other side of said power supply voltage and to the other end of said magnet coil, whereby when said first and second transistors are turned on said power supply voltage is across said magnet coil in one direction to cause an energizing current to flow in said coil increasing linearly to a level determined by the power supply voltage, the inductance of said coil and the length of time said first and second transistors are turned on,
a first diode connected to said one end of said coil and to said other side of said power supply voltage to conduct current upon being forward biased by said first transistor turning off to de-energize said coil,
a second diode connected to said other end of said coil and to said one side of said power supply voltage to conduct a circulating current for holding said coil energized upon being forward biased by said second transistor turning off, and
control means for simultaneously turning on said first and second transistors, said control means including time delay means to set the level of energizing current in said coil by turning off said first transistor after a predetermined time delay and means for turning off said second transistor at a predetermined time after said first transistor has been turned off whereby said energizing current circulates in said coil flowing from said one side of said power supply through said first transistor, through said coil, and through said second diode back to said one side of said power supply from the time said second transistor is turned off until said first transistor is turned off and after said first transistor is turned off said coil becomes de-energized as said first diode conducts current to said other side of said power supply.
45. The magnet coil driver circuit of claim 5 wherein said time delay means is a single shot multivibrator.
60. The magnet coil driver circuit of claim 5 wherein said first and second transistors are NPN transistors.
